GOLF CLUB HEAD

William L. Wettklaufer, Buffalo, N. Y.

Application October 12, 1938, Serial No. 234,652

3 Claims. (Cl. 273—77)

This invention relates to golf clubs, and it has particular reference to the provision of an improved head for a club of the wood type.

The club head of the present invention is adapted to be made of light metal, cast into the general form and shape of a wood type head, and wherein substantially the entire interior portion of the head is hollow, to provide a cavity in which may be located various adjustable weights for imparting to the club proper total weight, weight distribution, and balance. An important feature of this invention is to provide durable and rugged means for gaining access to this cavity in which the weights are disposed, and, specifically, this feature resides in the provision of a cover plate for the entire top surface of the head, so located that it will not be torn off by repeated impacts occurring during use.

The novel and inventive features of the invention, as set forth in the appended claims, will be more fully understood from a perusal of the following detailed and exemplary description of specific embodiments thereof, illustrated in the accompanying drawing, wherein:

25 Fig. 1 is a perspective view of the club head as viewed by the player at address;

Fig. 2 is a top view of the head with the cover removed;

Fig. 3 is a section on the line 3—3 of Fig. 2;

30 Fig. 4 is a section on the line 4—4 of Fig. 2;

Fig. 5 is a perspective view of the weight plate which is shown in inverted position;

Fig. 6 is a top view similar to Fig. 2 of another embodiment of the invention.

35 As shown in Fig. 1, the club comprises a head 10 and a shaft 11 which may be interconnected in any desired manner. As herein illustrated, the connection follows the teachings of my prior Patent No. 2,067,556, patented January 12, 1937, 40 whereby, through the provision of a polygonal socket 12 on the head and a complementary eccentric polygonal extension on the shaft, the head and shaft may be given various positions of alignment with respect to each other. Inasmuch as the prior patent explains this matter extensively, it is deemed unnecessary to illustrate or discuss this phase of the club at greater length.

The head 10, shown in plan in Fig. 2, is advantageously formed by casting a light metal, such as an aluminum alloy, with an integral base 13, striking face wall 14, and encircling wall 15. The wall 14 is substantially plane compared to the wall 15, which, as shown in Fig. 2, is substantially semi-cylindrical, and, as shown in Fig. 3, is 55 of progressively less height from the striking face

14 to the back of the head. There is thus formed a large open chamber 16, occupying the entire inner area of the head, and in which, as will be hereinafter described, are located adjustable weights for balancing the club.

5 The upper edges of the walls 14 and 15 are recessed or sunk to provide a continuous ledge or shoulder 17, which, as best shown in Figs. 3 and 4, rises abruptly into the upper traces of the walls, to form thrust surfaces for a cover plate 21. The 10 cover 21 is preferably formed of sheet metal, and is given a configuration and size to fit snugly within the shouldered portions of the walls, bearing both against the outer walls and on the continuous ledge 17. The head wall 15 is also formed 15 with a number of bosses 22 which are tapped and countersunk, as shown by the reference numeral 23. The cover 21 is also drilled and depressed, as indicated by the numeral 24, at its points of registry with the tapped bosses 22. Hence, when the 20 cover 21 is applied to the head, there is a continuous bearing contact with the ledge 17 and the shouldered portions of the walls 14 and 15, and the cover is flush with the upper traces of the walls. Additionally, the interengaging counter- 25 sunk and depressed portions 23 and 24 on the head and cover provide an interlocking engagement between the parts, thus rigidly securing the cover on the head against all impact forces, and removing destructive shear loads from the screws 30 26 which are applied to hold the cover in position.

I may note here that this continuous contact and interlocking engagement has been found highly advantageous, since, if the cover is not rigidly applied to the head, the repeated impacts 35 from blows may cause the screws to shear off, thus rendering the club unacceptable for play until repaired. In the invention as herein described, it will be observed that the shear loads are taken up by the walls and cooperating counter-sunk and depressed portions, thereby relieving the screws from all service except the positioning of the cover in its intended location.

40 It may also be noted that, in practice, the cover 21 substantially covers the entire top area of the club head, as shown in Fig. 1. By plating or enamelling the upper surface of the cover with a non-reflective surface, glare of bright sun light in the player's eyes is avoided. The colors may be varied among clubs in the same set, or between 45 different sets, thus permitting the player to identify the club readily.

45 The chamber 16 is utilized to house a manually adjustable weight mechanism. As illustrated in Figs. 2 to 5, this consists of a segment shaped 50

55

plate 30 which is pivotally mounted on a stud 31 carried in a boss 32 in the base portion 13. A nut 33 and lock washer 34 on the stud permits the plate to be anchored in any desired radial position. As an aid to securing the plate, the peripheral edge thereof is formed with a depending tooth 35 which may be positioned in any one of a plurality of notches 36 formed in the base 13. Radially disposed slots 37 in the plate 30 are supplied to receive a bolt 38, which may carry any number of auxiliary weights in the form of washers 39 secured by a nut 41.

By loosening the nut 33, the plate may be positioned so that a major portion of its weight is directed to the toe of the club adjacent the striking face (Fig. 2) or to any other radial position to a point of extreme adjustment where the weight is disposed between a stop lug 40 in the heel portion of the chamber and the last notch 20 36a (dotted lines, Fig. 2) where the weight is definitely within the sweet spot of the head. By varying the number of washers 39 and shifting their position in the slots 37, finer shadings of weight distribution may be obtained, and it will 25 be apparent that the center of the total weight mass may be brought to any desired position.

As shown in Fig. 5, the plate 30 may be mounted on the stud 31 in inverted position with the tooth 35 thereof in an inoperative position to 30 permit free swinging movement of the plate and attached weights. In this instance, the lock washer 34 is omitted and the nut 33 is screwed down to the shoulder 31a of the stud 31. This arrangement follows the teachings of my prior 35 Patent No. 2,098,445, patented Nov. 9, 1937, where it is shown that at the top of the backstroke the club is in a horizontal position and the weight drops to rest against the stop lug 40, thus relieving the player of a portion of the cantilever strain of the loaded club head. As the 40 club is swung, centrifugal force brings the weighted plate against the toe of the club, where its full force is available upon impact with the ball.

45 In Fig. 6 there is shown an adjustable weight structure which will give results comparative to the structure of Fig. 2. The head 50 is similar to the head 10, with the addition of a transverse wall 51 having an angular boss 52 formed in its central portion. Diagonally opposed pads 53 and 54 are formed in the interior of the head chamber, and the former contains a socket 55 while the latter is slotted as indicated by the numeral 56. The boss 52 also contains a slot 57. A 50 threaded stud 58 is positioned in the aligned slots and socket 55, and it is secured by nuts 59 disposed on opposite sides of the boss 52. The stud 58 carries a number of washers 61 which are clamped against the pad 53 by a nut 62. It will 55 be apparent that the stud is readily demountable from the chamber when it is desired to remove several of the washers or when a rearrangement of the washer location is indicated. For example, if toe weighting, as shown, is not desired, the washers may be positioned on one or both sides of the angular boss 52, or against the heel pad 54.

As in the first embodiment of the invention, the cover 60 caps the chamber C and conceals and protects the weight structure, and it is removable for easy access.

It will be observed that the cover structure is the same in both embodiments of the invention, and in both cases the cavity of the head is as

coextensive with the area of the head as is practically indicated, thus providing a large chamber in which adjustments may be made. Access to the weights is effected through the top of the head, and, by placing the cover plate on top, there is no likelihood of its being worn through, as would occur if the plate were on the bottom of the head. Obviously, it is within the skill of those versed in the art to replace the specific weights shown with others designed to accomplish the same purposes.

I claim:

1. In a golf club, a head comprising an integral metallic shell having bottom and upstanding walls defining an open chamber therein, a pivot member secured to the bottom of said shell, a plate pivotally carried by the pivot member, a plurality of radially spaced teeth in the shell bottom, a tooth in said plate engageable with one of the teeth of said shell, said upstanding walls being formed with a continuous shouldered ledge, a cover for said chamber snugly fitting within said ledge, and interconnecting and interlocking means for securing said cover to said ledge.

2. A golf club head comprising an integral metallic shell provided with a receiving socket for a shaft; a series of relatively thin walls rigidly reinforced so that they will enclose a compartment of maximum capacity occupying substantially the entire interior volume of the head, said compartment being provided with an opening at the top extending over substantially the entire top area of the club head, the top rim of said compartment being provided with a continuous shouldered ledge, tapped and conically countersunk reinforcing bosses formed on the interior of said wall areas and terminating in said ledge, a top cover plate adapted to interfit said rim and said ledge and to be held in position thereby against lateral displacement, said plate being formed with conically depressed portions, said portions being provided with apertures positioned to align with said tapped formations and to interlock with said countersunk formations, screws 45 removably engaging said plate with said tapped portions, and readily accessible manually adjusted weights supported within said compartment for varying the balance and weight of the club head.

3. A golf club head comprising relatively thin walls rigidly reinforced so that they will enclose a compartment of maximum capacity occupying substantially the entire interior volume of the head, said compartment being provided with an opening at the top extending over substantially the entire top area of the club head, the top rim of said compartment being provided with a continuous shouldered ledge, conically countersunk reinforcing bosses formed on the interior of said wall areas and terminating in said ledge, a top cover plate adapted to interfit said rim and said ledge and to be held in position thereby against lateral displacement, said plate being formed with conically depressed portions, said 60 portions being provided with apertures positioned to align with and to interlock with said countersunk formations, attaching means removably engaging said plate with said head, and readily accessible manually adjusted weights supported 65 within said compartment for varying the balance and weight of the club head.
